US00D882071S

(12) **United States Design Patent** (10) **Patent No.:** **US D882,071 S**
(45) **Date of Patent:** **** Apr. 21, 2020**

(54) **AUTOINJECTOR WITH REMOVABLE AUTOINJECTOR CAP**

(71) Applicant: **AMGEN INC.**, Thousand Oaks, CA (US)

(72) Inventors: **Brian Stonecipher**, Newbury Park, CA (US); **Dheeraj Gupta**, Simi Valley, CA (US); **Sigrid Moeslinger**, New York, NY (US); **Masamichi Udagawa**, New York, NY (US)

(73) Assignee: **AMGEN INC.**, Thousand Oaks, CA (US)

(**) Term: **15 Years**

(21) Appl. No.: **29/644,412**

(22) Filed: **Apr. 17, 2018**

Related U.S. Application Data

(63) Continuation of application No. 29/548,001, filed on Dec. 9, 2015, now Pat. No. Des. 822,198.

(57) **CLAIM**

The ornamental design for an autoinjector with removable autoinjector cap, as shown and described.

DESCRIPTION

FIG. 1 is a perspective view showing a new design for an autoinjector with removable autoinjector cap, showing the removable cap disposed on the autoinjector;

FIG. 2 is a top view of the autoinjector with removable autoinjector cap of FIG. 1;

FIG. 3 is a bottom view of the autoinjector with removable autoinjector cap of FIG. 1;

FIG. 4 is a front view of the autoinjector with removable autoinjector cap of FIG. 1;

FIG. 5 is a right-side view of the autoinjector with removable autoinjector cap of FIG. 1;

FIG. 6 is a rear view of the autoinjector with removable autoinjector cap of FIG. 1;

FIG. 7 is a left-side view of the autoinjector with removable autoinjector cap of FIG. 1; and,

FIG. 8 is a perspective view showing the autoinjector with removable autoinjector cap of FIGS. 1-7 with the removable autoinjector cap removed from the autoinjector.

The broken lines show portions of the design that form no part of the claimed design.

1 Claim, 5 Drawing Sheets
